Watson E. Coleman attorney

UNITED STATES PATENT OFFICE.

JOHN J. SPILLANE, OF WASECA, MINNESOTA.

CHIMNEY CLEANER.

Application filed July 23, 1921. Serial No. 487,068.

To all whom it may concern:

Be it known that I, JOHN J. SPILLANE, a citizen of the United States, residing at Waseca, in the county of Waseca and State 5 of Minnesota, have invented certain new and useful Improvements in Chimney Cleaners, of which the following is a specification, reference being had to the accompanying drawings.

10 This invention relates to chimney cleaners and the essential object of the invention is to provide a device of this character of simple construction which is cheap to manufacture and which may be speedily operated to clean 15 a flue or chimney from any accumulation of soot or other foreign matter.

Another object of the invention is to provide a flue cleaner which is adjustable to accommodate itself to all ordinary size flues or 20 chimneys and which is so constructed that it will clean every particle of the chimney, irrespective of the amount of adjustment necessary. In a great many flue cleaners that are adjustable, the adjustment separates 25 the brushes or cleaning elements so that they miss a large portion of the surface of the flue or chimney and thus fail to clean the same properly. This invention absolutely avoids such a defect and is also adapted to accommodate 30 itself to chimneys of varying diameter throughout their length, such as chimneys which are larger at the bottom than at the top.

A further object of the invention, therefore, 35 is to provide a device of this character which will adjust itself automatically to the various irregularities of a flue or chimney which cannot stick or wedge in the flue and which will not injure the lining of the chimney in any manner.

A still further object of the invention is the provision of a device of this character which will effectively clean a chimney having either a rectangular or circular flue and 45 which will automatically accommodate itself to any irregularities in the cross sectional dimensions of the flue as will be more fully apparent hereinafter.

Further objects of the invention will appear as the following specific description is read in connection with the accompanying drawings which form a part of this application, and in which:

Figure 1 is a side elevation of the cleaner 55 arranged in a circular flue with the diameter

of the flue slightly less than the width of the cleaning brushes;

Figure 2 is a horizontal section on the line 2--2 of Figure 1,

Figure 3 is a view similar to Figure 2 60 showing the type of brushes employed for a rectangular flue,

Figure 4 is an elevation taken at right angles to Figure 1 showing the method of adjusting the brushes to fit the flue, and

Figure 5 is a detailed elevation of a modified form of operating member.

Referring more particularly to the drawings, 1 represents the operating rod or shaft which may be in the form of a pipe section or solid, as is found most desirable. At the upper end of the shaft, as shown in Figure 1, I provide an eye 2 to which an operating cable or chain 3 is attached. In Figure 5 I have shown the upper end of the rod 1 threaded to receive extension rods 4 by which the cleaner may be pushed through the flue instead of allowed to drop by reason of its weight, as in Figure 1. The lower end of the rod is provided with an eye 5 to which a suitable weight may be attached where the weight of the device itself is insufficient to carry it through the flue.

Secured to the rod intermediate its ends is a head 6 in the form of a cross bar and pivoted to the outer ends of this bar are the brush supporting and carrying arms 7, normally forced away from each other by the leaf springs 8 which are secured to the rod 1 and bear against the inner sides of the arms 7, thus normally acting to throw the lower ends of the arms outwardly in opposite directions and bring the brushes 9, carried upon the lower ends of the arms, into engagement with the flue wall, which has been indicated at 10. The brushes shown in Figures 1 and 2 are each substantially semi-circular in outline and have passing through the backs thereof the attaching bolts 11 which pass through the lower ends of the arms and have threaded thereon the nuts 12, and if desirable, suitable lock nuts, not shown. When the nuts 12 are clamped

up on the bolts, the brushes will be held in any adjusted position and it will be understood that they may be rotated upon the bolts or be stationary with the bolts and the bolts rotated in the arms so as to secure any adjustment angularly of the arms whereby brushes of greater width than the diameter 110

of the flue may be adjusted to operate in said flue and to contact all over one side thereof, as will be readily understood from inspection of Figures 2 and 4. The brushes 5 shown in Figures 1 and 2 are semi-circular and when properly adjusted upon the arms are adapted to completely fill the flue, while the brushes shown in Figures 3 and 4 are rectangular in outline, being substantially 10 oblong and are adapted to engage opposite sides of a rectangular flue.

When the brushes shown in Figures 3 and 4 are used, they are adjusted to completely cover opposite sides of the flue and 15 the device is lowered into the chimney by means of the cable or chain 3 and worked up and down either with or without the weight, according to conditions, until opposite sides of the rectangular flue have 20 been completely cleaned. The device is then turned a quarter revolution so as to operate against the other sides of the rectangular flue and the operation proceeded with as before. In a circular flue the device 25 may be operated up and down in a similar manner and turned whenever desired without removing the same from the flue.

It will be noticed that by adjusting the 30 brushes in a rotary direction upon the arms that I am enabled to completely cover each side of the flue and by utilizing the freely pivoted arms and the springs 8, the brushes are constantly kept in contact with the walls of the flue irrespective of any

variation or irregularity in the cross sectional dimension thereof, thereby insuring contact of the brushes with the entire surface of the flue which effectively cleans the same at all points.

Instead of using the cable or chain 3 and 40 lowering the device into the flue by reason of gravity, I may attach to the rod 1, as shown in Figure 5, a sectional rod 4 by which the cleaner may be pushed downwardly into the flue and as it is removed, the 45 sections can be disconnected.

While I have illustrated a specific embodiment of my invention, I wish it to be clearly understood that various changes and modifications may be made without in any 50 way departing from the spirit or scope of the appended claim and many of these changes are contemplated and will be resorted to in practice.

What I claim is:

55
In a flue cleaner, a supporting head, arms freely pivoted to said supporting head, springs for normally forcing the free ends of the arms outwardly in opposite directions, and brushes adjustable in a rotary 60 direction upon the free ends of the arms, said brushes having a length equal to or greater than the width of the flue to be cleaned.

In testimony whereof I hereunto affix my 65 signature.

JOHN J. SPILLANE.
